UNITED STATES PATENT OFFICE

ALFRED J. JOHNSON, OF GRAND RAPIDS, MICHIGAN, ASSIGNOR TO YORK BAND INSTRUMENT COMPANY, OF GRAND RAPIDS, MICHIGAN

TROMBONE

Application filed August 5, 1929. Serial No. 383,691.

This invention relates to improvements in slide trombones and it relates particularly to the improvement of the slide.

The objects of the invention are:

- 5 First, to provide such a slide which will be very easy in operation and in which binding, due to slight defects or damage to the outer tube, are avoided.
- 10 Second, to provide an improved arrangement of the slide shoe, carrying the same by the outer member of the slide as distinguished from the inner.

15 Objects pertaining to details will appear from the description to follow. A preferred embodiment of my invention is illustrated in the accompanying drawing, in which:

Fig. 1 is a side elevation view of a trombone embodying the features of my invention.

20 Fig. 2 is an enlarged detail elevation view of the slide structure.

The parts will be identified by their numerals of reference which are the same in both the views.

25 1, 1 are the frame members of the trombone connected by the cross handle 2. 3, 3 are the inner slideway members which are plain, straight tube members coupled by the cross loop 41. 5 are the shoes which are coupled to the telescope tube members by the 30 sleeves 6, 6. The shoes 5 are each provided with an inner spiral lubricant groove 51. The sleeves 6, 6 are connected by the cross handle 7 by which the entire slide is manipulated in playing the instrument.

35 The tube members 4 have a bore of about four thousandths of an inch larger than the slideway members 3, and consequently if they become slightly dented or otherwise injured or are slightly irregular in form, they 40 do not bind on the slideway and manipulation is free and easy as a consequence. A slight blow on the outer member 4 does not interfere with the free operation of the structure.

I desire to claim this structure in its specific 45 form.

Having thus described my invention, what I claim as new and desire to secure by Letters Patent, is:

50 In a slide trombone, the combination with the instrument frame of a pair of inner slide-

way tubes open at their inner ends secured to the frame thereof, telescope tube members loosely surrounding the same in spaced relation connected by a loop at their outer ends, slideway shoes having inner spiral lubricant 55 grooves and disposed at the inner ends of said outer tube members, and outer sleeves connecting and supporting the said shoes on the said outer tube members, whereby in the manipulation of the instrument, the shoes are 60 reciprocated along the inner slideway members and the telescope tubes are maintained out of contact with the inner tubes.

In witness whereof I have hereunto set my hand.

ALFRED J. JOHNSON.
